UNITED STATES PATENT OFFICE

JAMES E. LANDERS, OF NEW YORK, N. Y., ASSIGNOR OF ONE-THIRD TO THOMAS C. DEXTER, OF PEARL RIVER, NEW YORK, AND ONE-THIRD TO JAMES H. McCARTHY, OF BROOKLYN, NEW YORK; MARGARET A. DEXTER EXECUTRIX OF SAID THOMAS C. DEXTER, DECEASED

AUTOMATIC STOP MECHANISM FOR SHEET FEEDERS

Application filed October 14, 1925, Serial No. 62,431. Renewed February 27, 1930.

The invention relates to apparatus serving to convey sheet material to another machine for subsequent operation thereon and to such other machine, and it is particularly applicable to sheet feeding machines and sheet folding or analogous machines when used together, that is to say, when the sheet folding machines are supplied with material directly from the sheet feeding machines.

10 An object of the invention is to provide an automatic, efficient and adequate means of interrupting the operation of a normally continuous feeder when for any reason a sheet fed into the folder, or other machine of analogous character into which the feeder sends the sheets, fails to pursue its normal course therein or after sheets of a predetermined number have been delivered to the folder or similar machine.

20 It sometimes happens that a sheet will not pursue its normal course through a folder for some reason, as, because a corner of the sheet has been turned or an edge torn or the sheet has been given a wrong direction. In such an event the sheet may become rumpled and impede the normal progress through the feeder of following sheets, thus causing what is known in the art as a "choke up", that is to say, causing the disturbed sheets to form 30 a mass, which mass may so clog the machine as to interrupt its operation or indeed damage some of its parts. In addition to the damage done to the machine, stock is destroyed, time is lost by the operator in clearing 35 the machine and restoring it to running order and on occasion in recounting sheets.

Further objects of the invention are to provide means for interrupting the operation of a sheet feeder which means shall be 40 simple in construction and operation, easily accessible and attachable, and inexpensive. These and other objects of the invention will in part be obvious and in part be more fully set forth in the following description.

45 The invention consists in the novel parts, improvements, combinations, and features of construction herein shown and described.

In the accompanying drawings, which are referred to herein and form part hereof, is 50 illustrated a preferred embodiment of the

invention, the same serving in connection with the description herein to set forth the principles of the invention.

Of the drawings:

Fig. 1 is a longitudinal section through the discharge end of a sheet feeding machine and an upper part of a sheet folder, together with parts of an automatic stop mechanism constructed in accordance with the invention;

Fig. 2 is a plan view of certain parts shown in Fig. 1;

Fig. 3 is a sectional view on an enlarged scale of the ratchet and detent mechanism shown at the left in Fig. 1, the detent being shown in this view in normal inoperative 65 position;

Fig. 4 is a face view on an enlarged scale of the detent mechanism shown in Fig. 3;

Fig. 5 is an enlarged side elevation of the clutch and clutch-operating mechanism used 70 in the stop mechanism, showing the same in "running" position;

Fig. 6 is a view similar to Fig. 5 with some parts broken away and showing the mechanism in "stop" position; and

Fig. 7 is a detail sectional view on the line 75 7-7 of Fig. 6.

Referring in detail to the drawings, there is illustrated therein a preferred embodiment of the invention, shown as used with a sheet 80 feeding machine and a sheet folder, the latter being supplied with material by the sheet feeder. As has been said, the prime object of the invention is to provide means for automatically stopping the sheet feeder and preventing the feeding of any more sheets into 85 the folder when, for any reason whatsoever a sheet already in the folder fails properly to pursue its normal course through the folder.

In pursuance of this object and according to the invention, means are provided for automatically stopping the sheet feeder at a predetermined time, as when a sheet should have reached a certain position in its course through the folder. If, however, the sheet 95 in the folder does pursue its course through the folder in a normal manner and reaches said position at the predetermined time, the mechanism will be brought into play by the sheet itself which will prevent the operation 100

of the said automatic stopping means with the result that both feeder and folder will continue to operate until the supply of sheets is exhausted when the feeder will cease to operate.

As shown in Fig. 1 sheets of paper P are placed in a feeder 9 and are fed forward by a series of drop rollers 11 mounted upon a shaft 12. The raising and dropping of these rollers 11 is controlled by a cam 13, mounted upon cam shaft 14, and acting upon a bell crank lever 15 pivoted upon a shaft 16. One arm 17 of said lever 15 engages a lever 18 rotatably mounted at one end upon a shaft 19 and freely engaging at its other end the shaft 12 upon which the drop rollers 11 are mounted, all as clearly shown in said Fig. 1. The sheet of paper thus fed forward from the paper P is engaged by drop rollers 21 and rollers 22, said drop rollers 21 being mounted upon a shaft 23, see Fig. 2, and said shaft 23 being freely mounted upon ends of arms 24, one arm only being shown. At their opposite ends said arms 24 are rigidly mounted upon a rock shaft 26 upon which is also rigidly mounted another arm 27 the opposite end of which engages a cam 28 mounted upon the shaft 14. The arm 27 is raised and lowered by the cam 28, thus raising and lowering the rock shaft 26 and with it the arms 24, the latter raising and lowering the shaft 23 carrying the drop rollers 21. The sheet is fed by said rollers 21 and 22 to the folder rollers 29, mounted upon shaft 31, and folder rollers 32 mounted upon the shaft 33. By said folder rollers the sheet is fed to the first fold gage where it is now in position to be acted upon by the first folder shown generally at 34. The constructions thus far described are standard machines and no further description of said machines or of their operation will be given except in such part as may be necessary in order to explain the present invention as used with said machines. When the sheet has reached the first fold gage safely and if it be without defect, it will contact with a finger 36 and thus actuate certain mechanism through the operation of which the sheet will be permitted to continue its course through the folder and which will be presently described.

The present invention contemplates, as has been stated, providing automatic mechanism for stopping the feeder after the passage of each sheet when sufficient time has elapsed for such sheet to have reached a certain point in its journey through the folder or other machine; and further providing mechanism for preventing the operation of said stopping mechanism if the sheet reaches said point in proper condition. To this preventing mechanism further reference will presently be made. In choosing the point at which to stop the feeder, it should be noted that in common practice such mishaps as occur to sheets in their progress through the feeders and

folders occur before the sheet has reached or should have reached its position in the folder for the first folding operation, and, also, that any defects in a sheet will have been manifested by that time. Therefore, means are provided for stopping the feeder when sufficient time has elapsed for the sheet to have reached position ready for the action of the folder 34, as indicated in Fig. 1. Preferably and as shown, said means comprise a cam 37, mounted upon said shaft 14, against which cam the roller 38 on the arm 39 of the bell crank lever 40, mounted on shaft 41, is held by the tension of a spring 42 which is secured at one end to said lever 40 and at its other end to a shaft 43. On the lever arm 39 is a pin 44 which engages a lever 46 mounted on a shaft 47, the lever 46 being held normally against the pin 44 by a spring 48 wound on and secured at one end to said shaft 47 and at its opposite end engaging another part of the feeder. Under the tension of the spring 42, see Fig. 1, the roller 38 follows the low side 49 of the cam 37 and the pin 44 thus forces downwardly the lever 46, and so rotates the shaft 47. On the outside end of said shaft 47 is a lever 51 on which in its forward portion is mounted a pin 52, see Fig. 2, said pin normally holding in raised position a lever 53 which is connected to the clutch throwout arm 54 of the feeder. The clutch mechanism, generally designated C, see Fig. 2, includes a disk 55 on the rim of which is mounted a spur 56. As the shaft 47 is rotated, as above described, it moves downwardly the lever 51 and with the latter the pin 52, which permits the arm 53 to drop. This latter arm carries a pin 53^a which also drops with the arm and is now engaged by said spur 56, as the disk 55 revolves. With the continued movement of said disk the lever 53, thru the action of the spur 56 on the pin 53^a, is drawn forwardly to the left, and with it the clutch throwout arm 54, from the operative position shown in Fig. 5 to the "stop" position, shown in Fig. 6, in which the clutch throwout arm 54 disengages the clutch and the sheet feeder ceases operating.

Mounted on the lever 53 is another pin 57 arranged to engage a lever 58 mounted on a shaft 59, said lever 58 being held against the pin 57 by a spring 61, one end of which is firmly engaged by the shaft 59 and the other end by the framework, see Figs. 6 and 7. Secured to said shaft 59 and arranged at an angle thereto, see Fig. 7, is another lever 62, having a notched end, and said lever 58 also has an extension 63, which latter member is projected inwardly at nearly right angles to the lever 58 and then forwardly, and with a further slight inward curve, see Figs. 6 and 7. As the arm 53 is moved forwardly to the left, the lever 58 under the tension of the spring 61 follows it and the notched end of the lever 62 comes under a roll stud 64 on the

arm 27, thus insuring that said arm 27 and the feed rolls 21 will be held up away from the paper. As the lever 58 swings to the left, the extension 63 carried by said lever 5 moves a loose lever 66 rotatably mounted on the framework thru a slot in the supporting casting, thereby raising up the lever 53 so that when the machine is restarted and said lever 53 returns to its former position, it will 10 be held away from the spur 56 on the clutch disk 55 for one revolution or until the arm 27 drops, the stud 64 hitting a projection 68 from the end of the loose lever 66, and returning said loose lever 66 to its normal 15 position. After this the lever 53 is held up by the cam 37 and a rack member presently to be described. Without this the feeder would stop again before making a revolution. The feeder is started by pushing a 20 rod 69 fastened to the throwout arm 54 and which runs to the front of the feeder. It will be obvious that the cams are timed with the various parts so that all will coordinate to bring about the desired result. 25 It will be seen that with a construction as thus far described, the feeder will be automatically stopped whenever a sheet fed into the roller should have reached the first folding position or has reached such position 30 with certain defects. Means are provided, however, to continue the normal operation of the feeder and folder if the sheet has reached the folding position in normal course and in proper condition. As shown, see Fig. 1, a 35 rod 71 is connected at one end to the bell-crank lever 40 and at its opposite end to a lever 72 pivoted on a bracket 73 and having its lower arm 74 arranged to engage a rack bar 76. This rack bar extends forwardly 40 thru an orifice 77 in a bracket 78 mounted on the folder. Rotatably mounted on the bracket 78 and loosely mounted on the same pivot as the finger 36 and controlled in its movements by an extension on the upper 45 part of said finger, as shown in Fig. 3, is a detent 79 adapted to engage the teeth of the rack bar 76 and prevent its forward movement. Said detent is normally held out of locking position with said teeth by the finger 50 36 thru the weight of an extension 81 of said finger which normally keeps the finger 36 in the position shown in Fig. 3. With the construction thus described it will be seen that as soon as a sheet has reached the first folding 55 position in the folder, its edge, if the sheet is in proper condition, will contact with the finger 36 and move the same into the position shown in Fig. 1, thus allowing the detent 79 to drop into engagement with the 60 teeth of the rack bar 76 and locking the latter against movement. It will further be evident that the spring 42 will also be prevented from exerting its tension on the bell-crank lever 40 so as to make the arm 39 and roller 38 follow the low face of the cam 37

and thereby pull down the lever 46, and thus setting in motion the mechanism which stops the feeder as hereinbefore explained. If, however, a sheet fails for any reason to contact with said finger 36, said finger and detent 79 will preserve their positions, as shown in Fig. 3, and the automatic stopping means above described will be allowed to work. The finger 36 and extension 81 are balanced so that the pressure of the contacting sheet will be sufficient to move the finger and detent into proper position. The time for the arrival of the sheet in first folding position is calculated so as to synchronize properly with the movements of the other parts necessary for the proper operation of the machine. It will be noted also that the device is useful with signatures, as when the last sheet of a signature has been fed to the folder, the feeder will stop. More machines, also, can be attended to by an operator.

It will be seen that a machine constructed according to the invention as hereinbefore described will carry out the objects of the invention as above enumerated, besides possessing many other advantages which will be apparent to those skilled in the art.

The invention is not limited to the precise construction shown and described, as many changes may be made in the details thereof without departing from the main principles of the invention or sacrificing its chief advantages.

I claim:

1. In mechanism of the type described the combination of sheet feeding mechanism, means for automatically stopping the operation of said feeding mechanism, a sheet folding mechanism including a folding unit and sheet advancing means intermediate the folding unit and the sheet feeding mechanism, said sheet advancing means operating to advance the fed sheets to the folding unit in position to be acted upon thereby, and means actuated by the sheet when so positioned for rendering the stopping means inactive.

2. In mechanism of the type described, the combination of sheet feeding mechanism, means for automatically stopping the operation of said feeding mechanism, a sheet folding mechanism including a folding unit in relation to which the sheet is positioned for folding, and means actuated by the sheet when so positioned for rendering the stopping means inactive, said sheet actuated means comprising a movable member operatively connected with said stopping means, and a lock for said movable member in position to be actuated by the sheet to hold said movable member against movement.

3. In mechanism of the type described, the combination of sheet feeding mechanism, means for automatically stopping the operation of said feeding mechanism, a sheet folding mechanism including a folding unit in

relation to which the sheet is positioned for folding, and means actuated by the sheet when so positioned for rendering the stopping means inactive, said sheet actuated 5 means comprising a movable toothed member operatively connected with said stopping means, and a movable locking detent for said member normally disengaged therefrom and arranged to be moved by the sheet into engagement with said member to hold the same 10 against movement.

4. In mechanism of the type described, the combination of sheet feeding mechanism, means for automatically stopping the operation of said feeding mechanism, a sheet folding mechanism including a folding unit in relation to which the sheet is positioned for folding, and means actuated by the sheet when so positioned for rendering the stopping 15 means inactive, said sheet actuated means comprising an endwise movable ratchet bar, a rocking lever pivoted to the bar for moving it endwise, a connecting rod from said lever to the stopping mechanism, a 20 spring acting on said rod, and a movable locking detent for said bar normally disengaged therefrom and arranged to be moved by the sheet into engagement with the bar to lock the same against movement.

30 5. An automatic stop mechanism for a sheet feeder and a sheet folder including in combination, means for automatically stopping the operation of the feeder, a pivotally mounted lever, a rod at one end engaging an 35 arm of said lever, a spring engaging the opposite end of said rod and forming part of said stopping means, a rack engaging the opposite end of said lever and arranged to be reciprocated thereby, and a detent arranged to 40 be placed in locking arrangement with said rack by contact of a sheet in said folder, whereby said rack will be held against movement and thereby said lever and rod will be held against movement and said spring prevented from functioning.

45 6. An automatic stop mechanism for use with a sheet feeder and a sheet folder including in combination, means for moving the clutch bar of the feeder into stop position, 50 and a cam for actuating said means, said cam being mounted on the shaft of the feeder controlling the feed rollers and being timed to operate when a sheet fed into the folder should have reached folding position, and 55 means for preventing the actuation by said cam of said first named means, said means being actuated by the sheet when it has reached said folding position.

60 7. An automatic stop mechanism for use with a sheet feeder and a sheet folder including in combination, an arm engaging the clutch bar of the feeder and provided with a 65 projecting pin, and a spur projecting from the rim of the clutch disk adapted to engage said pin, whereby on the rotation of the disk

said arm will be moved and throw the clutch bar into stop position, and means for raising said arm and pin out of the path of said spur when the sheet should have reached a predetermined position in the folder.

70 8. An automatic stop mechanism for use with a sheet feeder and a sheet folder including in combination, an arm engaging the clutch bar of the feeder and provided with a projecting pin, and a spur projecting from the rim of the clutch disk adapted to engage 75 said pin, whereby on the rotation of the disk said arm will be moved and throw the clutch bar into stop position, and means for raising said arm and pin out of the path of said spur when the sheet should have reached a predetermined position in the folder, said means being actuated by contact with the sheet.

80 9. An automatic stop mechanism for use with a sheet feeder and a sheet folder including in combination, an arm engaging the clutch bar of the feeder and provided with a projecting pin, and a spur projecting from the rim of the clutch disk adapted to engage 85 said pin, whereby on the rotation of the disk said arm will be moved and throw the clutch bar into stop position.

90 10. An automatic stop mechanism for use with a sheet feeder and a sheet folder including in combination, an arm engaging the 95 clutch bar of the feeder and provided with a projecting pin, and a spur projecting from the rim of the clutch disk adapted to engage said pin, whereby on the rotation of the disk said arm will be moved and throw the clutch 100 bar into stop position, and means for raising said arm and pin out of the path of said spur.

105 11. An automatic stop mechanism for use with a sheet feeder and a sheet folder including in combination, means for moving the clutch bar of the feeder into stop position, a cam, and a lever rolling on said cam for actuating said means, and means for preventing the rolling of said lever on the low face of said cam.

110 12. An automatic stop mechanism for use with a sheet feeder and a sheet folder including in combination, means for moving the clutch bar of the feeder into stop position, a cam, and a lever rolling on said cam for actuating said means, and means actuated by contact of the sheet for preventing the rolling of said lever on the low face of said cam.

115 13. An automatic stop mechanism for use with a sheet feeder and a sheet folder including in combination, means for moving the starting mechanism of the feeder into stop position, a cam, and a lever rolling on said cam for actuating said means, and means actuated by contact of the sheet for preventing 120 the rolling of said lever on the low face of said cam.

125 14. An automatic stop mechanism for a sheet feeder and a sheet folder including in combination, an arm engaging the clutch bar 130

of the feeder and provided with a projecting pin, a clutch disk provided with a spur projecting from the rim thereof and adapted to engage said pin, whereby on the rotation of the disk said arm will be moved to throw the clutch bar into stop position, means for lifting said arm out of the path of said spur for a predetermined period, and means for keeping said arm in raised position thru a revolution of said clutch disk, said means including a lever rotatably mounted in said feeder and arranged to engage said arm and keep it in said raised position, means for moving said lever into operative position, and means for returning said lever to its normal position.

15. An automatic stop mechanism for a sheet feeder and sheet folder including in combination, rollers in the feeder for feeding the sheet to the folder, means including an arm for feeding the sheet to the folder, means including an arm for raising the rollers out of operative position, a second arm having a roll stud thereon, and means for 20 raising said first arm comprising a third arm engaging the clutch bar of the feeder and provided with a projecting pin, a clutch disk provided with a spur projecting from the rim thereof and adapted to engage said pin, 25 whereby on the rotation of the disk said arm will be moved to throw the clutch bar into stop position, a shaft mounted in said feeder, a lever rigidly mounted on said shaft and normally held in engagement with the said 30 pin, and a second lever mounted on said shaft and adapted to engage said roll stud, whereby upon the movement of said third arm said second lever will be moved to engage said roll stud and lift said first arm out of 35 operative position.

40 In testimony whereof, I have affixed my signature hereto.

JAMES E. LANDERS.
